[57] CLAIM

The ornamental design for a variable heat glue application
gun, as shown and described.

DESCRIPTION

FIG. 1 is a front, top and side perspective view of the
variable heat glue application gun showing my new design;
FIG. 2 is a front elevational view thereof;
FIG. 3 is a rear elevational view thereof;
FIG. 4 is an end elevational view thereof;
FIG. 5 is an end elevational view thereof;
FIG. 6 is a top plan view thereof; and,
FIG. 7 is a bottom plan view thereof.
The electrical cord has been shown broken away in FIGS. 1
through 5 for the purpose of indicating indeterminate length.
